[57] CLAIM

The ornamental design for a ventilating cover for container, as shown and described.

DESCRIPTION

FIG. 1 is a top perspective view of a ventilating cover for container showing my new design;

FIG. 2 is a rear perspective view thereof;

FIG. 3 is a top plan view thereof;

FIG. 4 is a front elevational view thereof;

FIG. 5 is a rear elevational view thereof;

FIG. 6 is a bottom plan view thereof;

FIG. 7 is a right side elevational view thereof, the left side being a mirror image;

FIG. 8 is a sectional view taken in the direction of the arrows 8—8 of FIG. 3.

Fig 1.
